UNITED STATES PATENT OFFICE

148,114

DESIGN FOR A BRACELET

Floyd W. Fruett, Salem, Oreg., and Paul N. Jewell,
Beulah, Mich.

Application May 10, 1946, Serial No. 129,569

Term of patent 14 years

(Cl. D45—4)

To all whom it may concern:

Be it known that we, Floyd W. Pruett and Paul N. Jewell, both citizens of the United States, residing at city of Salem, county of Marion, State of Oregon and city of Beulah, county of Benzie, State of Michigan, have invented a new, original, and ornamental Design for a Bracelet, of which the following is a specification, reference being had to the accompanying drawing, forming a part thereof.

We claim:

The ornamental design for a bracelet, substantially as shown.

FLOYD W. PRUETT.
PAUL N. JEWELL.
